GARMENT WITH BREATHING SLEEVE
ACTION

Irving Isaac Flasher, St. Paul, Minn.

Application December 7, 1948, Serial No. 63,883

5 Claims. (Cl. 2—115)

1

This invention relates to the sleeve connection for shirts, coats and like garments, and has for its purpose the provision of an opening under the arm for proper ventilation and a flap for covering the opening.

It is an object of this invention to provide a sleeve connection of the kind to be more particularly described hereinafter to permit a breathing arm action to ventilate the arm and body of a wearer, and to provide fresh air for the action of the arm without exposing the arm or body. In the process of moving the arm, the flap or pivot piece of the garment covering the opening moves away from the remaining part of the garment permitting air to freely circulate through the opening and under the flap or pivot piece and thereby decrease the perspiration.

A garment formed in this manner is advantageous for use by people engaged in sporting activities, such as golf, bowling, curling and other sports. When the arm is down, the pivot or flap covering the breathing opening is hidden and cannot be seen. The structure of such a garment is simple and does not entail a large expenditure. The construction creates a breathing pocket actuated by the use of the arm. By reason of the fuller cut of the garment, there is also a free arm movement.

In a garment formed in this manner it will be possible to vary the size, shape and even direction of the flap or pivot piece.

With the above and other objects in view, my invention consists in the arrangement, combination and details of construction disclosed in the drawings and specification, and then more particularly pointed out in the appended claims.

In the drawings:

Figure 1 is a front elevation partly broken away of a garment formed according to an embodiment of my invention;

Figure 2 is a side elevation, partly broken away, showing the arm in a raised position;

Figure 3 is a horizontal section taken on the line 3—3 of Figure 2;

Figure 4 is a vertical section taken on the line 4—4 of Figure 2;

Figure 5 is a top plan view of the arm blank formed according to an embodiment of this invention; and

Figure 6 is a side elevation of a modified form of this invention.

Referring to the drawings, the numeral 10 designates generally a shirt or other body-covering garment having a sleeve 11 extending from the upper end thereof. The body 10 of the garment

2

may be formed of front and rear body sections 12 and 14 in the manner of conventional shirts and similar garments currently in use. The front and rear body sections 12 and 14 may be secured together along the side edges, as denoted by the numeral 15 in the drawings.

The body 10 is provided at the upper end thereof with an armhole opening 16 cut out from the front and rear sections 12 and 14, respectively. The armhole is noted by the numeral 16 defining the peripheral edge thereof. The cut-out armhole is formed partially in the front section 12 and partially in the rear section 14.

The sleeve 11 is formed in a tubular manner by securing the free edges of a flat blank together underneath the arm in the manner of a conventional shirt. The end of the tubular sleeve member is adapted to be secured about the periphery of the armhole cut-out portion 16. However, in order to provide an opening between the sleeve 11 and the body 10 of the shirt, the sleeve is not connected to the body portion immediately below the arm. In this manner an opening is provided below the arm pit for the desired ventilation. The sleeve 11 is adapted to be secured about the major portion of the periphery of the armhole by conventional stitching, not shown, in the drawings.

In order to provide for the closing of the opening provided at the free edge between the sleeve 11 and body 10, a flap member 20 is formed integrally with the sleeve 11 and is adapted to be secured to the body portion 10 a slight distance downwardly from the free edge 16 defined above.

In the formation of the sleeve 11 it has been found desirable to provide a portion of a flap along the side marginal edges of the blank from which the sleeve is to be cut. Substantially triangular flap sections 18 and 19 are cut in the formation of the blank. The flap sections 18 and 19 form a continuation of the side edges of the sleeve 11, and when the sleeve is completely formed, that is, the side edges of the blank thereof stitched together, the flap sections 18 and 19 will define a substantially triangular flap 20.

When the arm 11 is stitched to the body 10 about the peripheral edge of the armhole cut-out, the lower portion of the armhole will be free and the flap or pivot piece 20 will overlie the free portion of the armhole and extend downwardly along the length of the body portion 10. The free end of the flap 20 is adapted to be secured by stitching, as denoted by the numeral 21, a short distance downwardly from the armhole. As the upper end of the flap 20 is formed as an inte-

gral part of the sleeve 11, the upper end of the flap 20 will be carried by the sleeve. The side edges of the flap 20 will be left free, and unsecured at any point along their length, so that when the arm is in the lowered position, a clear opening will be provided from the free edge of the cut-out armhole to the exterior of the garment.

In the formation of the tubular section 11 the edges of the end to be connected to the body portion 10 will be hemmed in a conventional manner, as clearly shown in Figure 3 of the drawings.

In the use and operation of the garment constructed according to an embodiment of this invention, an opening is provided under the armpit of the wearer to provide for the proper ventilation of the arm and body. Normally, the armpit opening between the sleeve section 11 and the body 10 will be substantially closed by the close position of the free edges of the sleeve and body. When the arm is raised, the armpit opening will be considerably enlarged, and as the flap 20 overlies the free edges of the opening, this flap will conceal both the opening and the body of the wearer below the opening.

In Figure 6 there is shown a modified form of this invention, wherein the flap 20a is formed in substantially the same manner as the flap 20 described above. The flap 20a will be carried by the body portion 10a rather than by the arm portion 11a. The flap 20a will close the free edges of the opening provided by the connection of the arm 11a to the body 10a in substantially the same manner as described above for the connection of the sleeve 11 to the body 10. In Figure 6 the tab or flap 20a will be formed integrally with the body section 10a, which includes the body-forming sections 12a and 14a, and the upper or free end of the flap 20a will be secured by stitching 21a to the sleeve 11a a short distance upwardly from the free edge thereof. As in the garment described in Figures 1 to 5, above, the side edges of the flap 20a will be free and separate from the remaining portion of the garment.

Having thus described my invention, what I claim is:

1. A garment of the kind described comprising a body-covering member formed with a cut-out armhole, a sleeve member secured to said body member about the major portion of the edge of said armhole and free therefrom below the armpit providing a ventilating opening, and a substantially triangular flap overlying said opening and having one end secured to one of said members and having the other end secured to the other of said members with the sides of the flap free for admission of air to said opening.

2. A garment of the kind described comprising a body-covering member formed with a cut-out armhole, a sleeve member secured to said body member about the major portion of the periphery of said armhole and free therefrom

below the armpit providing a ventilating under-arm opening, and a flap formed on one end of said sleeve member and secured at the free end thereof to said body member and overlying said opening, said flap being free along the side edges thereof permitting the passage of air to said opening in the elevated position of said sleeve and closing said opening in the lowered position of said sleeve.

- 5 3. A garment of the kind described comprising a body-covering member formed with a cut-out armhole, a sleeve member secured to said body about the major portion of the periphery of the armhole and separate therefrom at the lower 15 edge of said armhole providing an under-arm ventilating opening, and a flap formed integrally with one of said members overlying said opening and secured at the free end thereof to the other of said members, said flap having free side 20 edges permitting the passage of air to said opening in the elevated position of said sleeve and closing said opening in the lowered position of said sleeve.

4. A garment of the kind described comprising 25 a body-covering member formed with a cut-out armhole, a sleeve member secured to said body about the major portion of the periphery of the armhole and separate therefrom at the lower edge of said armhole providing an under-arm 30 ventilating opening, and a flap formed integrally with said sleeve overlying said opening and secured at the free end thereof to the body, said flap having free side edges permitting the 35 passage of air to said opening in the elevated position of said sleeve and closing said opening in the lowered position of said sleeve.

5. A garment of the kind described comprising a body-covering member formed with a cut-out 40 armhole, a sleeve member secured to said body about the major portion of the periphery of the armhole and separate therefrom at the lower edge of said armhole providing an under-arm 45 ventilating opening, and a flap formed integrally with said body member overlying said opening and secured at the free end thereof to said sleeve member, said flap having free side edges permitting the 50 passage of air to said opening in the elevated position of said sleeve and closing said opening in the lowered position of said sleeve.

IRVING ISAAC FLASHER.
